(57) **CLAIM**

The ornamental design for an electric ice scraper, as shown and described.

DESCRIPTION

FIG. 1 is a perspective view of the electric ice scraper according to the present invention;

FIG. 2 is a top view thereof;

FIG. 3 is a bottom view thereof;

FIG. 4 is a side view thereof (the opposite side being a mirror image);

FIG. 5 is a front end view thereof; and,

FIG. 6 is a rear end view thereof.

The broken line environmental showing is for illustrative purposes only and forms no part of the claimed design.
